UNITED STATES PATENT OFFICE

118,030

DESIGN FOR A DIRECTORY

Adolph J. Wethington, Dayton, Ohio

Application March 3, 1939, Serial No. 83,317

Term of patent 14 years

To all whom it may concern:

Be it known that I, Adolph J. Wethington, a citizen of the United States, residing at Dayton, in the county of Montgomery and State of Ohio, have invented a new, original, and ornamental Design for a Directory, of which the following is a specification, reference being had to the accompanying drawing, forming a part thereof.

Fig. 1 is a perspective view of a directory, showing my new design.

Fig. 2 is an end elevation of my new design.

Fig. 3 is a front elevation of my new design.

I claim:

The ornamental design for a directory, as shown.

ADOLPH J. WETHINGTON.
